(57) **ABSTRACT**

A chrysanthemum plant named 'VENUS' characterized by its medium sized blooms with purple ray florets and prolific branching; natural season flower date August 26–31; blooming for a period of 5 weeks.

3 Drawing Sheets

1

BACKGROUND OF THE INVENTION

'VENUS' is a product of a breeding and selection program for outdoor pot mums (garden mums) which had the objective of creating new chrysanthemum cultivars with a decorative type flower, a natural season flower date around August 26–31; blooming for a period of 5 weeks. The new plant of the present invention comprises a new and distinct cultivar of Chrysanthemum plant 'VENUS' is a seedling resulting from the open pollination among groups of chrysanthemum cultivars maintained under the control of the inventor for breeding purposes. The new and distinct cultivar was discovered and selected as one flowering plant by Rob Noodeljik on a cultivated field in Rijsenhout Holland in August 2000. The plant has been asexually reproduced by cuttings in greenhouses at Rijsenhout Holland. The new cultivar has been found to retain its distinctive characteristics through successive propagations.

BRIEF DESCRIPTION OF THE DRAWINGS

The present invention of a new and distinct variety of chrysanthemum is shown in the accompanying drawings, the color being as nearly true as possible with color photographs of this type.

FIG. 1 shows a plant of the cultivar in full bloom.

FIG. 2 shows the various stages of bloom of the new cultivar.

FIG. 3 shows the petiole and foliage of the new cultivar.

DESCRIPTION OF THE INVENTION

This new variety of chrysanthemum is of the botanical classification *Chrysanthemum morifolium*. The observations and measurements were gathered from plants grown outdoor in Rijsenhout, Holland under natural day length and temperature and planted week 22 in 2000 And 2001. The natural blooming date of this crop was August 26–31 (week 35). The average height of the plants was 27 cms. No growth retardants were used. No tests were done on disease or insect resistance or susceptibility. No tests were done on cold or drought tolerance. This new variety produces medium sized blooms with purple ray florets blooming for a period of 5 weeks.

2

From the cultivars known to inventor the most similar existing cultivar in comparison to 'VENUS' is 'MELISSA'. When 'MELISSA' and 'VENUS' are being compared the following differences are noticed: The differences of 'MELISSA' and 'VENUS' are (1) Flower color. The color of 'VENUS' is more dark purple than that of 'MELISSA'. (2) Natural flowering date. 'VENUS' flowers earlier than 'MELISSA'.

The following is a description of the plant and characteristics that distinguish 'VENUS' as a new and distinct variety. The color designations are taken from the plant itself. Accordingly, any discrepancies between the color designations and the colors depicted in the photographs are due to photographic tolerances. The color chart used in this description is: The Royal Horticultural Society Colour Chart, edition 1995.

Table 1. Botanical Description of cultivar 'VENUS'

- Bud:**
Size.—Small ;cross-section 1.0 cm, height 1.2 cm.
Outside color.—Red-purple 60 A.
Involucral bracts.—2 rows, length 7 mm, width 3 mm.
Involucral bracts among disc-florets.—Not present.
Involucral bracts color.—Green 138 B.
- Bloom:**
Type.—Decorative.
Height.—Flat 1.5 cm.
Size.—Medium.
Fully expanded.—5.0–5.5 cm.
Number of blooms per branch.—Approx. 5–7 blooms per branch.
Performance on the plant.—5 weeks.
- Seeds.**—Produced in small quantities, ovate grey-brown 199A, 1½ mm in length.
- Fragrance.**—Typical chrysanthemum, slightly.
- Color:**
Center of the flower.—Immature red-purple 60 A.
Mature yellow 13 A.
Color of upper surface of the ray-florets.—Red-purple 60 A.
Color of the lower surface of the ray-florets.—Red-purple 60 A.

<i>Tonality from distance.</i> —A garden mum with purple flowers and a yellow disc in the mature stage.	<i>Stem color.</i> —Yellow-green 147 B.
<i>Color of the upper surface of the ray-florets at aging of the plant.</i> —Red-purple 60 C.	<i>Stem strength.</i> —Strong.
Ray florets:	<i>Stem brittleness.</i> —Present.
<i>Texture.</i> —Upper and under side smooth.	<i>Stem anthocyanin coloration.</i> —Absent.
<i>Number.</i> —140–150.	<i>Length of lateral branch.</i> —From top to bottom 13–14 cm.
<i>Cross-section.</i> —Flat.	<i>Lateral branch color.</i> —Yellow-green 147 B.
<i>Longitudinal axis of majority.</i> —Reflexing.	<i>Lateral branch, attachment.</i> —Flexible.
<i>Length of corolla tube.</i> —Short 0.4 cm.	<i>Branching (average number of lateral branches).</i> —
<i>Ray-floret margin.</i> —Entire.	Prolific with 9–10 breaks after pinching.
<i>Ray-floret length.</i> —2.2–2.4 cm.	<i>Peduncle length.</i> —5.5–6.0 cm.
<i>Ray-floret width.</i> —0.4–0.6 cm.	<i>Peduncle color.</i> —Yellow-green 147 B.
<i>Ratio length/width.</i> —High.	<i>Natural season blooming date.</i> —August 26–31.
<i>Shape of tip.</i> —Pointed.	Foliation:
Disc florets:	<i>Color.</i> —Upper side yellow-green 147 A. Under side yellow-green 147 C.
<i>Disc diameter.</i> —0.7 cm.	<i>Size.</i> —Small; length 4.5 cm, width 3.0 cm.
<i>Distribution of disc florets.</i> —Numerous, visible at mature stage.	<i>Quantity (number per lateral branch).</i> —10–12.
<i>Shape.</i> —Tubular.	<i>Shape.</i> —Ovate.
<i>Color.</i> —Yellow 13 A.	<i>Texture upper side.</i> —Glabrous.
<i>Receptacle shape.</i> —Conical raised.	<i>Texture under side.</i> —Pubescent.
Reproductive organs:	<i>Venation arrangement.</i> —Palmate.
<i>Stamen (present in disc florets only).</i> —Thin. 3 mm in length.	<i>Shape of the margin.</i> —Serrated.
<i>Stamen color.</i> —Yellow-green 144 A.	<i>Shape of base of sinus between lateral lobes.</i> —Round.
<i>Pollen.</i> —Present in a small quantity.	<i>Margin of sinus between lateral lobes.</i> —Converging.
<i>Pollen color.</i> —Yellow 7 A.	<i>Shape of base.</i> —Acute — Truncate.
<i>Styles.</i> —Thin.	<i>Apex.</i> —Cuspidate.
<i>Style color.</i> —Yellow-green 144 A.	
<i>Style length.</i> —4 mm.	
<i>Stigma color.</i> —Yellow-green 144 A.	
<i>Stigma width.</i> —1 mm.	
<i>Ovaries.</i> —Enclosed in calyx.	
Plant:	
<i>Form.</i> —When grown as a spray type pot-mum, outdoor mounded and round.	
<i>Growth habit.</i> —Spreading.	
<i>Growth rate.</i> —Rapid.	
<i>Height.</i> —27 cm.	
<i>Width.</i> —36–38 cm.	

<i>Stem color.</i> —Yellow-green 147 B.
<i>Stem strength.</i> —Strong.
<i>Stem brittleness.</i> —Present.
<i>Stem anthocyanin coloration.</i> —Absent.
<i>Length of lateral branch.</i> —From top to bottom 13–14 cm.
<i>Lateral branch color.</i> —Yellow-green 147 B.
<i>Lateral branch, attachment.</i> —Flexible.
<i>Branching (average number of lateral branches).</i> —
Prolific with 9–10 breaks after pinching.
<i>Peduncle length.</i> —5.5–6.0 cm.
<i>Peduncle color.</i> —Yellow-green 147 B.
<i>Natural season blooming date.</i> —August 26–31.
Foliation:
<i>Color.</i> —Upper side yellow-green 147 A. Under side yellow-green 147 C.
<i>Size.</i> —Small; length 4.5 cm, width 3.0 cm.
<i>Quantity (number per lateral branch).</i> —10–12.
<i>Shape.</i> —Ovate.
<i>Texture upper side.</i> —Glabrous.
<i>Texture under side.</i> —Pubescent.
<i>Venation arrangement.</i> —Palmate.
<i>Shape of the margin.</i> —Serrated.
<i>Shape of base of sinus between lateral lobes.</i> —Round.
<i>Margin of sinus between lateral lobes.</i> —Converging.
<i>Shape of base.</i> —Acute — Truncate.
<i>Apex.</i> —Cuspidate.

TABLE 2

Differences with the comparison varieties		
	'VENUS'	'MELISSA'
Color of the upper surface of the ray-florets	Red-purple 60 A	Red-purple 67 A
Natural flowering date	August 26–31	October 1–7

I claim:

1. A new and distinct variety of chrysanthemum plant as described and illustrated.
